ANTONINUS FARINA, OF NEW YORK, N. Y.

MACHINE FOR FOLDING AND SHAPING COLLARS.

SPECIFICATION forming part of Letters Patent No. 602,067, dated April 12, 1898.

Application filed February 17, 1896. Serial No. 579,549. (No model.)

To all whom it may concern:

Be it known that I, ANTONINUS FARINA, of New York city, in the county and State of New York, have invented a new and Improved 5 Machine for Folding and Shaping Collars, of which the following is a full, clear, and exact description.

The object of this invention is to provide a machine which is capable of folding collars 10 in a manner more expeditious and effective than heretofore, and also a machine in which this folding will be done without injuring the collar.

The invention consists in certain peculiar 15 features of construction and combinations of parts, which will be fully described herein-after and finally embodied in the claims.

Reference is to be had to the accompanying drawings, forming a part of this specification, 20 in which similar characters of reference indicate corresponding parts in all the figures.

Figure 1 is a side elevation of the machine. Fig. 2 is a plan view thereof. Fig. 3 is a vertical section taken through the disk and shaping-block, to be fully described hereinafter. Fig. 4 is a bottom plan view of the shaping-block shown in Fig. 3. Fig. 5 is a sectional elevation of the plate and shaping-block. Fig. 6 is a sectional view on the line 6-6 of 25 Fig. 5. Fig. 7 is a perspective view of a turn-down collar partly folded by the machine. Fig. 8 is a perspective view of a similar collar completely folded. Fig. 9 is a detail view showing one of the treadles. Fig. 10 is a detail view showing the connection of one of the clutch-sections with its shape, so as to slide thereon; and Fig. 11 is a detail view 30 showing one of the ball-and-socket connections.

40 In carrying out my invention I provide a table 10, supported on suitable legs 11, and this table supports the operative parts of the apparatus. Journaled in pedestal-bearings 12 is a shaft 13, having a pulley 14, over which a drive-belt may pass to impart to the shaft 13 a continuous rotary movement. The shaft 13 projects beyond the bearings 12 and carries at each end a clutch member 15. Pedestal-bearings 16 and 17 carry a rotary shaft 45 18, longitudinally alined with the shaft 13 and having a clutch member 19 splined on the end

adjacent to the shaft 13, the clutch member being adapted to mesh with the adjacent clutch member 15, so that the shaft 18 will be connected with the shaft 13. The pedestal-bearing 16 has an extended portion carrying a box 21, in which a shaft 22 is rotatably mounted, and the shaft 22 has its lower end rotatable in a step 23. The shaft 22 is driven from the shaft 18 by means of bevel-gears 24 and 25, respectively secured on the shafts 22 and 18.

Fixed on the shaft 22 is a disk 26, having a perpendicular peripheral flange 27, and having cloth 28 firmly stretched over each side 65 by means of spring-bands 29, which have a tendency to press the respective sides of the flange, so as to firmly clamp the cloth, as shown in Figs. 1 and 3.

Rising from the table 10 is a standard 30, 70 which has its upper end bifurcated and in which bifurcated end one end of a lever 31 is fulcrumed, the lever 31 having a rod 32 pivotally connected to its middle, and said rod extends downwardly through an opening in the 75 table and is pivotally connected to a treadle 33, by which the rod may be vertically reciprocated, a spring 34 being provided and embracing the rod to give the same a tendency to an upper position. The spring 34 is connected 80 with the table 10 and with the treadle 33.

The free end of the lever 31 is vertically alined with the flange 27 of the disk 26, and said free end of the lever carries a hollow block 35, having an open upper side over which 85 a lip 36 projects, said lip carrying burner-tips 37, with which the respective air and gas tubes 38 and 39 communicate. The under side of the block 35 is provided with a groove 40, which is curved in an arc equal to the arc of the 90 flange 27 and which is adapted to receive said flange as the lever 31 moves downwardly. At the inner side of the flange 27 the block 35 extends downwardly below the portion of the block at the outer side, as shown best in 95 Fig. 3. Fig. 4 illustrates a bottom plan of the block 35.

Fixed to the clutch member 19 is a grooved flange 41, in which a forked lever 42 operates, said lever being fulcrumed to the pedestal-bearing 17 and having its lower end extended 100 through a longitudinally-elongated slot in the

table 10, said lower end being attached to a flexible connection 43, passing over pulleys 44 and attached to the treadle 33, the disposition of these parts being such that when the 5 treadle is depressed to move the block 35 downward to engage the flange 27 the connection 43 will be operated to rock the lever 42 and engage the two clutch members 19 and 15, causing the shaft 18 to be driven from the 10 continuously-rotating shaft 13 the instant that the block 35 engages the flange 27. The lever 42 is pressed by a spring 63, so that the clutch member 19 will have a tendency to disengage the adjacent member 15. At other 15 times, however, the shaft 18 and the parts driven therefrom are motionless.

Journalized in a pedestal-bearing 45 is a shaft 46, one end of which is contiguous to the right-hand end of the shaft 13 and carries a clutch 20 member 47, splined on the shaft 46 and capable of movement to engage and disengage the clutch member 15, such movement being effected through the medium of a lever 48, fulcrumed on the pedestal 45 and having its 25 lower end operating through a longitudinally-elongated slot in the table 10, said end being attached to a connection 49, running over idler-pulleys 50 and passing downward to a treadle 51, carried by a vertically-movable rod 30 52, passed through the table 10 and having a ball-and-socket connection with a lever 53.

The lever 53 is fulcrumed by a ball-and-socket connection on a standard 54, rising from the table 10, and the lever 53 is also provided 35 with a ball-and-socket connection with a rod 55, connected to an eccentric 56, fixed on the shaft 46. By means of the eccentric 56 and the appurtenant parts the lever 53 is oscillated in a horizontal plane on the standard 40 54, and by means of the rod 52 the lever 53 may be raised and lowered at the end to which said rod is affixed.

The disposition of the clutch member 47 and the parts connecting said member with the rod 52 is such that when the rod is moved 45 downwardly to swing the right-hand end of the lever 53 in a similar direction the clutch member 47 will be engaged with the adjacent member 15, and a spring 57 is made to engage 50 the rod 52, so as to give said rod and consequently the parts to which it is attached an upward tendency. The spring 57 bears on the table 10 and is connected to the rod 52. The lower extremity of the rod 52 is provided 55 with a spur 58, adapted to engage the floor or other surface on which the table stands, so as to form a bearing for the rod 52, on which the same may oscillate under the influence of the movement of the lever 53.

60 Fixed to the table 10 is a standard 64, which rises perpendicularly therefrom and carries a plate 65, curved in an arc similar to that in which the right-hand end of the lever 53 moves. This plate 65 is covered with a sheet 65 of cloth 66, held by means of a curved loop 67 and a pin 68, the pin being passed through

the plate, so as to hold the loop from upward movement.

Fixed to the right-hand end of the lever 53 is a block 69, similar to the block 35 and having burner-tips 70, held by a clip 71 and in communication with the respective air and gas tubes 72 and 73. When the lever 53 is moved downwardly at its right-hand end, the block 69 will be made to engage the plate 65, 75 and the groove 74^a of the block 69 will receive the upper edge of the plate 65, while the downwardly-extended inner portion 75 of the block 69 will move along the inner side of the plate 65. 80

It will be seen that as the lever 53 is drawn downward at its right-hand end the clutch member 47 will be engaged with the disk 15 to cause the shaft 46 to rotate and the lever 53 to rock. When, however, the rod 52 is 85 permitted to rise, a spring 59 rocks the lever 48 to disengage the clutch member 47 and the adjacent member 15.

Each end of the table 10 is provided with a bowl 60, from the sides of which plates 61 90 upwardly project, and these plates carry a pair of rolls 62, formed of felt. The bowls 60 are adapted to contain water, and by means of the capillary attraction the rolls 62 will be constantly wetted, so that collars may be 95 wetted by contacting them with the rolls.

My invention is adapted for folding and shaping turn-down and roll collars and for shaping the wings of wing-collars. Turn-down collars are those shown in Figs. 7 and 100 8 of the drawings. Roll-collars are of the same general class except that they are much taller and that at the ends the fold is rolled or rounded, as distinguished from creased, as in Figs. 7 and 8, and wing-collars are those 105 which stand and are provided with wings extending out from the sides of the collar and respectively at the ends thereof.

In folding turn-down collars the collars are first taken from the washing process and 110 ironed flat in the usual manner. The collars are next wetted at the fold-line, where they are to be creased in the folding operation, so that the folding may be effected without breaking the fabric of the collars. The wetting of the collars as above described may be 115 effected by the rollers 62 or by any other suitable means. The collar, being now wetted at the fold-line, is placed over the flange 27 of the disk 26, so that the flange will bear against 120 the inner side of the fold-line and cause the collar to conform to the flange, so that the collar will be properly folded. The treadle 33 should now be operated to draw down the lever 31, so that the block 35 will descend and 125 cause the groove 40 to receive the flange 27. Immediately subsequent to this movement of the lever 31 the shaft 18 will start to revolve, and the disk will be moved in a similar manner, carrying the collar beneath the block 35 130 and through the groove 40, whereupon the collar will be shaped as shown in Fig. 7. By

means of the burner-tips 37 the block 35 is kept constantly hot, and the operation above described will iron the crease of the collar, so that no further work need be done toward 5 folding and creasing.

In laundering turn-down collars it is necessary to fold them into the form shown in Fig. 8, and this is done by the hands of the operative. In doing this work the collar will 10 be rumpled at points adjacent to the rear buttonhole, and in order to again smooth and shape this part of the collar I provide the mechanism at the right-hand side of the table 10. This work is done by placing the rear 15 portion of the collar, when shaped as shown in Fig. 8, over the upper edge of the plate 65, and the rod 52 is moved downwardly to engage the block 69 with the collar. Immediately subsequent to this movement of the 20 block 69 the lever 53 will be rocked and the block 69 moved along the collar, so as to perform the same operation performed by the block 35 and flange 27. The work of folding and shaping a turn-down collar is now complete. 25

In operating on roll-collars they may be folded on the flange 27 and shaped by the block 35 without the use of the plate 65 and block 69; but in order to prevent sharply 30 creasing the ends of the collar the block 35 is formed so that the ends of the groove 40 will be flared outwardly, as shown at 74 in Fig. 4. By these means the block 35 may be applied along the collar between its ends, but 35 the enlarged portions of the groove 40 will receive the rolled ends of the collar and prevent the same from being creased.

In operating on wing-collars the collar may be placed over the plate 65 and the wing 40 creased by means of the downward and horizontally-vibratory movement of the block 69. It is also possible to fold the wing on the flange 27 and with the coöperation of the block 35.

45 It will be seen that my invention both shapes and folds the collars. In addition to ironing and shaping the collar the blocks 35 or 69 will serve to smooth down any parts of the fiber which may project in a torn state 50 from the collar, thus making the collar regular at its crease and preventing it from irritating the neck of its wearer. The block 35 is so formed that its groove 40 will bear on the upper edge or crease of the collar and on 55 the inner side or band thereof, but not on the outer side of the collar to any appreciable extent. The inner side of the block serves to press against the collar and to form or shape the same, while by keeping the outer side of

the groove out of contact with the collar the 60 block is prevented from marking the face of the collar. By these means I provide a machine which will shape a collar and at the same time it folds the collar, and this operation is performed by the inner side of the 65 groove bearing against the collar-band.

Having thus described my invention, I claim as new and desire to secure by Letters Patent—

1. In a machine for folding and shaping collars, the combination with a drive-shaft, of a flanged disk, a shaft carrying said disk, a driving mechanism for said shaft, a movable block grooved to receive the flange of the disk, and means for simultaneously moving 70 the block into and out of engagement with the flange of the disk and throwing the driving mechanism of the disk-carrying shaft into and out of gear with the drive-shaft, substantially as described. 75

2. In a machine for folding and shaping collars, the combination with a drive-shaft, of a flanged disk, a shaft carrying said disk, a driving mechanism for the shaft, a clutch mechanism between the said shaft and the 85 drive-shaft, a pivoted block grooved to receive the flange of the disk, and means for simultaneously raising and lowering the block and operating the clutch to throw the driving mechanism of the disk-carrying shaft into 90 and out of engagement with the drive-shaft, substantially as described.

3. The combination with a frame, of a shaft capable of being continuously driven, a second shaft, a clutch capable of connecting the 95 two shafts, a disk having a flange, the disk being driven from the second shaft, a pivotally-mounted lever, a block carried by the lever and capable of engaging the flange of the disk, mechanism for moving the lever, and a 100 connection between said mechanism and the clutch, the connection being capable of engaging the members of the clutch simultaneously with the downward movement of the lever, substantially as described. 105

4. In a machine for folding and shaping collars, the combination with a drive-shaft, of a flanged disk, a shaft carrying said disk, a driving mechanism for the shaft, a clutch connecting said mechanism with the drive-shaft, 110 a pivoted block grooved to receive the flange of the disk, a treadle connected with the pivoted block, and means for operating the clutch from the treadle, substantially as described.

ANTONINUS FARINA.
